P. HINKLE.
MACHINE FOR GRINDING AND AMALGAMATING ORES.
No. 63,979. Patented Apr. 16, 1867.

United States Patent Office.

PHILIP HINKLE, OF SAN FRANCISCO, CALIFORNIA, ASSIGNOR TO HIMSELF
AND CHARLES S. CAPP, OF THE SAME PLACE.

Letters Patent No. 63,979, dated April 16, 1867.

IMPROVED MACHINE FOR GRINDING AND AMALGAMATING ORES.

The Schedule referred to in these Letters Patent and making part of the same.

TO ALL WHOM IT MAY CONCERN:

Be it known that I, PHILIP HINKLE, of the city and county of San Francisco, in the State of California, have invented a new and improved Arrangement of Machinery for Grinding and Amalgamating Ores of Gold and Silver and other Minerals; and I do declare that the following is a full and exact description thereof, reference being had to the accompanying drawings, and to the letters of reference marked thereon, making a part of this specification.

In this ore-grinder and amalgamator the main improvements made consist in having the principal part of the grinding effected by means of perpendicular mullers or grinding plates thrown laterally, by centrifugal force, against a circular, perpendicular grinding surface, formed by the side dies arranged against the walls of the basin or pan, and the peculiar shape and arrangement of the cover by which a continual flow of the ground pulp from the circumference to the centre is secured, until the amalgamation is completed.

The power is applied in any effective manner to the central driving-shaft A, which carries the hollow cone A', having four or more horizontal arms B B, to the under surfaces of which are attached the ordinary flat mullers or grinding plates B' B', moving over the segmental dies or bed plates H H, fitting within the bottom of the pan or tub. On each of the arms B B is a perpendicular round pin, C C, by which are carried and allowed to play loosely the perpendicular muller-hangers E E, which are also supported by the lips I I resting upon the smooth bearing surfaces D on the arm B which follows it. To the muller-hanger E is securely attached the perpendicular muller or grinder F, (which can be renewed when worn out.) By means of the slot J, or otherwise, provision is made for loading the muller-hanger E to counterbalance the loss of weight by wear of the surface of the muller or grinder F. The pressure of the flat mullers B B upon the under dies or grinding plates H is regulated by the screw O and set-screw P bearing on the head of the shaft A and raising or depressing the cone A' with its arms B B. When the arms B B are revolved the perpendicular mullers or grinders F F are thrown by centrifugal force against the perpendicular grinding surface formed by the dies G G, and between them the crushed ore, as it comes from under the horizontal mullers, is pulverized and amalgamated. The grooves M and N contain mercury, protected from the mullers and motion of the ore, and the amalgam there formed is drawn off through apertures K and L. In pulverizing and amalgamating a single charge of silver or other ores, the pulp is introduced at the centre around the shaft A and cone A' into the feeder T, and thence passing between the horizontal grinding surfaces, and afterwards between the perpendicular mullers F and the dies G, is carried by centrifugal force against the sides, and rising passes through apertures R R in the cover of the pan U, under the projecting flange V, and thence flows over the funnel-shaped portion of its upper surface, the ring W, which breaks the force of the current, and the groove S, containing mercury, and returning to the centre re-enters the feeder T, when the process is continued until the amalgamation is completed. For grinding and amalgamating continuously, as the pulp is supplied from the batteries of a crushing-mill, the feeder T is extended upwards as a funnel above the top of the cover of the pan, which is then made a simple convex lid, and the pulp as ground escapes from an annular aperture in the cover around the feeder. The raised edge of this aperture forms the head of a spout by which the pulp is carried off as fast as discharged. The metals liberated by the grinding are caught and amalgamated in the grooves M and N.

What I claim as my invention, and desire to secure by Letters Patent, is—

1. The employment of the renewable side dies G G to form a perpendicular grinding surface on the sides of the tub or pan, substantially in the manner and for the purpose described.
2. The employment of the perpendicular muller-hangers E E, loosely hung on the pins C C, carrying the renewable mullers or grinding plates F F, of the shape shown in the drawings, thrown and pressed laterally by centrifugal force against the perpendicular grinding surface G G, when the arms B B are revolved, with the supporting lip I and bearing surface D, upon the arms B B, by which arrangement the pressure is lightest at the feeding point and heaviest at the heel of the muller; and also the provision for loading the muller-hanger to counterbalance the loss of weight by wear of the face of the muller F, substantially in the manner and for the purpose described.
3. The shape and arrangement of the cover of the pan U, so as to form a flattened funnel-shaped dish with annular grooves S for mercury, and raised current-breaking ring W on its upper surface, the collar or projecting flange V, with the apertures R R under it, by which the escape of the pulp is permitted and its current directed so that it is returned to the centre and a continual circulation maintained.

PHILIP HINKLE.
